SOCKET DEVICE

Carl L. Knutson, Maywood, Ill., assignor to Cinch
Manufacturing Corporation, Chicago, Ill., a
corporation of Illinois

Application May 5, 1931. Serial No. 535,146

1 Claim. (Cl. 173—328)

My invention aims to provide improvements in socket devices for radio tubes and the like.

In the drawing which illustrates a preferred embodiment of my invention:—

5 Figure 1 is a plan view of a preferred embodiment of a socket member, parts thereof being illustrated by dotted lines;

Fig. 2 is an enlarged section taken on the line 2—2 of Figure 1; and

10 Fig. 3 is a section taken on the line 3—3 of Fig. 2.

While I have illustrated in the drawing one embodiment of my invention, it should be understood that my invention may be used in connection with various types and constructions of 15 socket members for similar purposes.

The socket member illustrated has a pair of plate members of thin insulating material (Fig. 2), one of which I shall term a base plate 1 having a series of apertures 2 formed therein and arranged in a circle at a spaced distance from the center of the base plate 1. The other plate member may be termed a bottom plate 3 and it also has a series of apertures 4 which are aligned 25 with the apertures 2 in the base plate 1.

Between the plate members 1 and 3 I have secured terminal members 5 of any suitable construction for alignment with the apertures 2 and 4, so that they may receive and make contact 30 with the "prongs" presented by a radio tube or like member (not shown). The terminal members 5 illustrated in the drawing are substantially the same as those more fully illustrated and described in the co-pending application of 35 Arthur W. Kimbell, Serial No. 375,924, filed July 5, 1929. These terminal members 5 have substantially tubular portions 6 extending from bases 7 located between the plate members 1 and 3 through the apertures 4 in the bottom plate 40 3, as clearly illustrated in Fig. 2. The plate members 1 and 3 are preferably spaced from each other by spacing means 8 (shown in dotted lines, Fig. 2) so that the tubular portion 6 of each contact member may expand and contract without interference from the plate member 3.

The base plate 1 and the bottom plate 3 are secured together by means of the tubular rivet 9 rectangular in cross-section (Figs. 2 and 3) so that the parts are held against accidental relative rotation.

The socket structure thus far described is in most respects substantially the same as the application referred to above and is merely for the purposes of a clear understanding of my invention which I shall now proceed to describe.

It has been found that objectionable noises have been present in radio and like apparatus due to electrical leaks or "spark jumps" from one terminal member to another terminal member in radio sockets having a series of terminal members relatively closely arranged as a part of the socket device. I have also found that in practice there has been some difficulty encountered in connection with the types of devices under consideration due to the fact that one or more 60 of the terminal members might be partially rotated thereby bringing some portion thereof into contact with an adjacent terminal member, thus causing a short circuit. In order to overcome the objections mentioned herein, I have provided 65 a third insulating member 10 which in the structure illustrated is located between the plates 1 and 3 and is secured in position against rotation by the rivet 9. The member 10 is provided with a number of radial arms 11 each of which 70 may be of a width substantially equal to the distance between the terminal members, as clearly illustrated in Figs. 1 and 3. While the member 10, as shown in the drawing, is star-shaped, it should be understood that the shape 75 of the device may be varied in accordance with the type of socket structure to which it is to be applied.

Since the arms 11 are of insulating material 80 they form spacing means which prevent contact between the terminal members 5 if one or more of them is accidentally turned. Furthermore, the arms 11 insulate the terminal members 5 one from the other, thereby effectively preventing 85 electrical leaks and "spark jumps" from one to 90 the other. This will be readily understood when consideration is given to the fact that one terminal member may be connected to a positive supply of electricity, while the adjacent terminal member may be connected to a negative supply 95 of electricity, and since in many cases the metallic parts of the terminal members are relatively closely arranged, it is apparent that there is a tendency for electricity to be attracted from one terminal member to the other, thus causing 100 "spark jumps" unless some insulating means is provided between the adjacent portions of the terminal members. While these "spark jumps" may not occur at such frequent intervals as to impair the operation of a device with which the 105 socket member is associated, nevertheless in connection with radio apparatus these "spark jumps" cause noises in the circuits which are audible in the reproducer.

My invention is particularly applicable to socket 110

members of the type illustrated and described wherein two relatively thin plates are used and are spaced from each other and also for sockets which include only a single plate beneath which the 5 terminal members are attached, the bottom plate 3 being omitted.

While I have illustrated and described a preferred embodiment of my invention I do not wish to be limited thereby, because the scope 10 of my invention is best defined by the following claim.

I claim:

A socket for use with radio tubes and the like comprising, in combination, two relatively thin 15

spaced plates of insulating material each having a number of apertures aligned with the apertures of the other and arranged in circles about the centers of said plates, contact-receiving members having flange portions assembled between said plates in alignment with said apertures and other portions extending through one of said plates and a third star-shaped plate of insulating material secured between said spaced apertured plates and having portions extending between those portions of said terminal members between said plates for the purposes described.
